UNITED STATES PATENT OFFICE.

EUGENE R. PHILLIPS, OF EAST PROVIDENCE, RHODE ISLAND.

AUTOMATIC MAGNET-WINDING MACHINE.

1,057,008.

Specification of Letters Patent.

Patented Mar. 25, 1913.

Application filed January 23, 1906. Serial No. 297,526.

To all whom it may concern:

Be it known that I, EUGENE R. PHILLIPS, a citizen of the United States, residing at East Providence, in the county of Providence and State of Rhode Island, have invented certain new and useful Improvements in Automatic Magnet-Winding Machines, of which the following is a full, clear, and exact description.

10 My invention relates to a machine for winding magnet spools, bobbins, coils, resistances, and all similar windings where bare or insulated wire is spirally applied to a supporting core or spool.

15 The principal object of the invention is to provide a machine of the general type set forth in my application No. 302,213, filed February 21, 1906, capable of winding the wire on its spool with smoothness and precision, and with sufficient speed to suit all commercial requirements. I further secure these purposes by a machine which is substantially automatic; not requiring any particular skill or difficult manipulation.

25 A further object of the invention is to construct a compact and simple machine, and which is adapted to receive spools of varying sizes and apply different grades and kinds of wire to form any desired shape 30 or character of coil.

35 A still further object of the invention is to provide for a reverse of the winding motion for the purpose of withdrawing the whole or a portion of the winding from a partly completed spool at any time.

With these and other objects in view my invention consists in the construction, combination, location and arrangement of parts hereinafter set forth and shown, and finally 40 particularly pointed out in the appended claims.

In the drawings, Figure 1 is a top or plan view of the principal portion of a winding machine embodying the principles of my invention; Fig. 2 is a front elevation of the same; Fig. 3 is an end view looking from the right in Figs. 1 and 2; Fig. 4 is a detail view of the wire carrying head and guiding arm; Fig. 5 is a detail view of part of the 45 reversing mechanism; Fig. 6 is a bottom view showing a largely diagrammatic representation of the spool and wire guiding arm; Fig. 7 is a side elevation showing the wire guiding and tensioning means which I employ; Fig. 8 is a front view of the same; Fig. 9 is a largely diagrammatic representa-

tion of the driving and wire withdrawing mechanism.

The application of metallic wires, whether bare or insulated, in spiral windings upon a core presents special difficulties, and so far as I am aware, no machine has been constructed up to the present time which will wind wire upon spools of any except very short lengths without requiring hand manipulation to properly reverse and direct the lead at the ends of the successive layers. The difficulty occurs by reason of the hard and resilient nature of the wire which cannot be forced to take an exact pitch or lead as is the case with a softer or fibrous material. Fibrous materials like threads and yarns can be positively led with a predetermined feed, and the material packed closely into a smooth layer regardless of whether the feed exactly corresponds to the diameter of the filament or not. Metallic wire is, however, round and hard and resilient and will not pack together like fibrous material so that if the layers are not led with their natural pitch, or, in other words, the feed suited to their diameters, and reversed at precisely the right instant, the successive turns will pile up or become spread apart, either of which conditions injures the electrical properties, and mars the symmetry of the winding.

If the wire is led to a continuously rotating spool and progressively fed axially thereof as the spool rotates the wire will coil itself about the spool, but whether or not this winding is in a smooth layer depends on having the proper tension in the wire, and having a slight amount of rearward inclination to the lead so that the wire will pack closely. If the tension varies or the direction of the lead is slightly changed, the resiliency of the wire comes into play so that it winds more or less closely than before, and this variation, taken together with the slightly varying diameter of metallic wires causes it to be almost impossible to make two windings exactly the same. Accordingly the time at which the lead of the winding reaches the head of the spool cannot be exactly predetermined; it varying with the tension, with the direction of the lead, with the resiliency and character of the wire, and irregularities in its insulation. This is the reason why ordinary spool winding machines cannot be used for winding wire, since the reversal in a positive way,

and at a predetermined point, cannot be arranged to suit varying conditions which occur. In carrying out my invention I secure the proper reversal of the wire in spite of the difficulties mentioned.

The essential principle which I make use of consists in guiding the wire under proper conditions of lead, inclination and tension, with a positive and predetermined feed during the main portion of the layers, providing at the same time for slightly varying conditions due to different resiliency and diameter and tension of the wire; and then provide what I term a compensating reverse which makes the reverse of the layer at the head of the spool regardless of the movement of the positive feeding device at this time, and depending solely on the needs and requisites of the reversal itself.

Stated in more specific terms my invention consists in positively guiding the wire to the spool during the major portions of its length, and guiding it from a non-positive feed, under proper conditions of tension and direction, at the end of the successive layers.

Referring now to the drawings, in which like parts are designated by the same reference signs, 1 indicates the main frame of the machine upon a portion of which are erected brackets 2 which serve to support a guiding rod 3. This rod serves as a guiding bed for a head stock 4 and tail stock 5 of the winding mechanism. The head stock 4 has a live spindle 6 therein, and is conveniently rigidly secured to the guiding rod 3 by a clamp nut 7.

8 designates the driving pulley upon the live spindle 6 by which it is rotated from any suitable source of power not shown.

The tail stock 5 is guided by a spline 9 upon the guiding rod 3, and may be clamped in any relation thereon by clamp nut 10.

11 designates the tail stock spindle. Both the live stock spindle 6 and the tail stock spindle 11 are provided with chucks 12, between which a spool or core may be clamped for the purpose of winding.

Parallel to the axes of the winding spindles above described I arrange a screw shaft 13 rotating in fixed bearings 14 and having a hand wheel 15 at one end and a gear 16 at the other. The gear 16 meshes with a train of gearing by which motion is communicated to the screw shaft 13 from the live spindle 6, first in one direction, and then in the other. Before considering the nature of these gear connections, however, I will describe the features of the wire guiding mechanism which constitute the most important feature of my invention.

The essential characteristic of the wire guiding mechanism is the combination of the positive means for guiding the wire

along the major part of the spool with the compensating reverse made by the movement of the wire itself. Referring particularly to Fig. 4, I have illustrated a practical form of wire guiding mechanism comprising a traveling head 17 which has an opening 18 internally threaded so as to engage the threaded shaft or lead screw 13. The traveling head 17 is additionally guided by an extension 19 having an eye 20 which encloses the longitudinal rod 21. Upon the forward side of the head 17 are a pair of projecting ears 22, which serve to guide the vertical threaded pin 23 having a spline 24 so as to be non-rotatable therein.

25 indicates a thumb nut engaging the threads upon the pin 23 so as to vertically adjust and maintain it at any desired vertical elevation.

The threaded rod or shaft 23 has secured thereto the wire carrying frame 26 which embodies standards 26' with a large guiding wheel 27 thereon, and also a depending part or sub-frame 26'', which is also rigid with the frame 26. Guided by the vertical axis 28 upon the frame 26 is a swinging arm 29 which I conveniently make in the triangular form shown in order to secure greater strength consistent with lightness.

30, 31 and 32 designate guiding wheels or rollers each having a grooved periphery for leading the wire into winding relation.

33 indicates a wire lock or holder for securing the free end of the wire between operations, and which may be formed of a pair of spring pressed disks similar to the ordinary tensioning means for sewing machines.

The various wheels 30, 31 and 32, and the lock or holder 33 are all carried by the swinging arm 29 in any relation, but preferably in that shown, in which the inner edge of the guiding wheel 30 is substantially in alignment with the vertical axis of the arm, so that the wire guided thereby from the wheel 27 will always be led to such wheel in a true tangential plane. The final or terminal guiding wheel 32 is carried in proximity to the winding spindle, and in a special relation therewith, as diagrammatically indicated in Figs. 4, 6 and 9. As seen from these figures the wire passes from the final or delivery roller 32 upward and slightly forward toward the tangential surface of the usual spool to be wound, which inclination is preserved or increased as the winding progresses. In this way a radial component of force is outwardly exerted upon the wire guiding arm by the tension of the wire itself, tending to hold the arm in its normal or perpendicular relation, but capable of swinging movement therefrom by the requisites of the feed, or other reason.

The swinging guide arm 29 oscillates

freely on its axis 28, except so far as controlled by the tension of the wire as above described, and a resistance appliance or dash pot 34 upon the sub-frame 26''. In practice I make use of a cylindrical cup 35 filled with oil or a viscous fluid and having wings 36 therein extending from a central stem 37. The stem 37 is geared to a segment 38 co-axial with the axis 28 so that the motions of the swinging guide arm 29 are transmitted to the stem 37 and wings 36, and the impedance due to the viscous fluid exerts a certain light resistance to the movements of the swinging guide arm.

I will now describe the connections by which the wire guiding head 17 is impelled in its to and fro movement upon the lead screw 13.

The live spindle 6 carries a pinion 39 which meshes with a large gear 40 on a counter shaft 41, which in turn carries upon its other end a change gear 42. The change gear 42 meshes with an idler 43 on an adjustable parallel shaft 44, which in turn is in mesh with a gear 45, also journaled at 46 upon the frame of the machine. The shaft 46 carries loosely mounted upon it the gears 47 and 48, which may be of different diameters, and which respectively operate the gears 16 and 49 both rigidly fixed upon the lead screw shaft 13. The gear 49 is directly in mesh with gear 48, while the gear 16 is driven from the gear 47 by an intermediate idler 50, so that its rotation is in the opposite or reverse direction therefrom when clutched into action. The pitch ratios are fixed at such values as to produce the same speed of the lead screw in its reverse as in its forward movement.

51 indicates a sleeve splined to the shaft 46 so as to be capable of independent longitudinal movement, and the ends of this sleeve are toothed or crowned, as shown at 52 and 53, so as to engage corresponding teeth or crowns 52' and 53' upon the gears 47 and 48. By this arrangement the sleeve 51 may be moved so that its teeth engage one or another of the gears 47, 48, whereupon such gear will be clutched to the sleeve 51 and will rotate with the supporting shaft 46. 54 indicates a collar surrounding the sleeve by which it is longitudinally moved.

I provide means for shifting the collar 54 and sleeve 51 so as to throw either of the gears 47 or 48 into operation to drive the lead screw in one direction or the other. In practice I have found that a hand reverse is ordinarily sufficient by reason of the compensating action of the swinging arm wire guide which I employ as above described. A convenient form of hand reverse is particularly illustrated in Fig. 5, although it is to be understood that this is merely an exemplary practical construction and any other hand or automatic reverse could be

used in lieu thereof. 55 indicates an arm or a lever connected to the clutch collar 54, by means of which the clutch sleeve can be shifted longitudinally so as to engage the teeth 52' and 53'. 56 denotes what I shall term a shifting and locking block, and which forms part of a mechanism for shifting the clutch and for holding it in either extreme position of its throw. In practice I make the block 56 with opposed inclined surfaces 57 and 58, and secure it to the rod 21 previously mentioned, which has a longitudinal movement within its containing supports, so that the block 56 is capable of reciprocating longitudinally. 59 and 60 denote pins having a vertical movement within their containing frame 61. The lower ends of the pins 59 and 60 are formed with a square point or shoulder 59' and 60', which respectively contact with and move upon the inclined cam surfaces 57 and 58. Each of the pins also has a vertical diametral slot therethrough, indicated at 62, and a notched bar 63, guided by the frame 61 extends through both of the slots 62, as clearly shown in Fig. 5. The upper and lower parts of the slots 62 within the pins have V-shaped shoulders as shown at 64, and the notches 65 of the bar 63 are formed to coöperate with the V-shaped shoulders of the pins, so that one pin is moved downward and positively locked in such position, while the other pin is moved upward and positively locked in said upward relation. When the transversely moving bar 63 is shifted to its other position, as, for example, to the right in Fig. 5, the pin 59 will be positively cammed upward and the pin 60 positively cammed downward, and both pins again locked in the new relation. The effect of this movement of the pins 59 and 60 is to throw the shifting and locking block 56 to and fro by the camming action of the shoulders 59' and 60' against the inclined walls 57 and 58. It is evident that the block is held at either extreme position, as, for example, in its right-hand position in the figure, by the continued opposed engagement of said shoulders and cam walls. 66 denotes a momentum lever which may be pivoted at 67 upon the shifting bar 63, and guided to oscillate when the bar is reciprocated, for the purpose of insuring a full throw of the lever.

The shifting bar 63 is moved to and fro by the lever 67^a, (Fig. 1) having a link connection 67^b therewith. The handle 67' of this lever projects upwardly into convenient reach of the operator, in case the machine is arranged for hand reverse. If the machine is made for automatic reverse, the automatic devices would, of course, be substituted for the lever 67^a. By the above mechanism it will be understood that the operator is able to effect an almost instant-

taneous reverse of the movement of the lead screw whenever her judgment determines that the layer has progressed sufficiently far to warrant it. On account of the high speed of the winding operation, and the nature of metallic wires, as above indicated, the reverse of the lead screw will occur an indefinite distance, varying anywhere from one to a dozen turns before the layer actually reaches the spool head, but the actual point of the lead screw reverse is immaterial on account of the compensating action of my wire guided swinging arm reverse, the operation of which will be hereinafter more fully stated.

The essential feature of the lead screw reverse is that it should be sudden, complete and locked in either thrown relation, and it is evident that the practical construction of reversing mechanism which I have described, accomplishes all of these purposes.

Wire supplying and tensioning means.—In addition to the mechanism for directly leading the wire upon the spool, I provide means for supplying it under proper tension, the nature of which is particularly indicated in Figs. 7 and 8. 68 designates the supply reel, which is the ordinary wooden reel, upon which copper wire is furnished by the manufacturers. This is supported by standards 69. 70 denotes an additional standard, having a rigid plate 71 at its upper end, from which depend stretched wires 72, which serve to guide a vertically movable carriage 73, carrying a pulley 74. 75 indicates a long tension spring attached to the plate 71 and to the carriage 73, so as to normally press the carriage upward. 76 indicates another standard, carrying the pulleys 77 and 78 in planes to guide the wire from the pulley 74 to a small guide pulley 79 upon the traveling head 17 of the winding machine proper. The relation of the pulleys 78 and 79 is such that the direction of the wire from one to the other coincides with the direction of movement of the wire carrying frame. From pulley 79 the wire passes upward and over the large grooved wheel 27 above referred to. The wire, designated as W, is initially led from the reel 68 over the tension pulley 74 and the various remaining pulleys 77, 78 and 79 to the winding mechanism. The reel 68 has a frictional resistance against rotation formed by the conical point 80 of one of its supporting journals, and the carriage 73 will be drawn upward until the tension of its spring balances the tension of the wire W. The spring tensioned carriage 73 compensates for the irregularities in the feed of the wire, it being evident that it will insure a substantially uniform tension, even if the length of the wire between the reel and the spool being wound varies during the various operations of the winding

process. For example, the to and fro motions of the wire carrying frame tend to slightly vary the length of wire between the reel and spool, but this slight variation is compensated for by the movements of the carriage 73.

Means for withdrawing or unwinding the wire from a partly completed spool.—Referring to Fig. 9, I have illustrated diagrammatically the essential features of the wire withdrawing or rewinding mechanism which I employ in practice. The reel 68 and the spool A to be wound are indicated in substantially the relative positions they occupy in practice, and the course of the wire is generally indicated by the line W. The conical friction member 80 is shown inserted into the reel 68 so as to give the necessary frictional engagement therewith. 81 indicates a pulley fixed to rotate with the cone 80 and connected by a belt 82 with a similar pulley 83 on a sleeve 84, forming part of a clutch 85 loose on the driving shaft 86. 87 denotes a similar clutch member on a sleeve 88 having a pulley 89, belted at 90 to the driving pulley 8, previously mentioned, on the winding spindle. 91 indicates a sleeve splined to the driving shaft 86 and adapted to be thrown into frictional engagement with the clutch members 85 or 87 by a treadle mechanism, designated as 92. It will be obvious that when the treadle is depressed to clutch the member 87 to the driving shaft, that the winding spindle is rotated to apply the winding, but that when the treadle is moved to clutch the member 85 to the driving shaft, that the reel 68 is driven reversely, so that the wire is re-wound thereon and withdrawn from the partially completed spool A which is capable of revolving idly for such purpose. The particular features of the clutches and belting arrangements, as above outlined, and illustrated in Fig. 9, are, of course, largely diagrammatic, merely serving to illustrate the essential features of the two clutches which can be frictionally engaged to drive the pulley, or reversely drive the wire containing reel, under the motions of a treadle. In practice the practical details will be considerably modified, as will be obvious to any mechanic skilled in the art.

From the above description the operation of the wire guiding, tensioning, withdrawing and lead screw reversing means will be sufficiently understood. These features while practically important are susceptible of being worked out in different ways, and I regard them as of inferior significance in relation to the features of the compensating swinging arm reversely guided by the wire itself to reverse the layers at the heads of the spools. I will now take up in detail the action of this important feature.

The operation of the compensating layer

reverse is as follows: Referring particularly to Fig. 6, which shows a bottom view, diagrammatically represented, the spool A is continuously rotated in the direction of the arrow and the wire passes from the guiding arm 29 on to the spool in a helical winding which feeds toward the right by virtue of the motion of the lead screw. It will be seen that the arm 29 has a force applied to it tending to maintain it in the perpendicular relation shown, on account of the tension of the wire itself, which exerts a radial component on the arm at its outer end. This force, together with that of the dash pot, is enough to keep the arm in rigid relation under ordinary circumstances, so that the wire is applied to the spool with a pitch corresponding to that of the lead screw. If by reason of a slightly changed diameter in the wire, or uneven resiliency, or other reasons, a coarser feed should be required, the swinging arm 29 can move ahead slightly with respect to the lead screw, so that the wire is not piled up on account of the positive feed of the lead screw. During this action the machine is operating very rapidly and as the layer approaches the head C of the spool, the mechanism is actuated which reverses the motion of the lead screw. As above stated, I employ either hand or automatic means for effecting this reverse, but in practice it is ordinarily sufficient to make use of the hand reverse since the operator, who is necessarily present during the winding, has nothing else to do at this time, and is capable of making the reverse at about the time required without any special mechanism for the purpose. This is the more true on account of the difficulty of effecting a prearranged automatic reverse at the proper instant required with respect to the condition of the layer. In any case, whether the reverse is made automatically or by hand, it is made preferably a number of turns before the lead of the wire has reached the head of the spool. On account of the high velocity of the rotation it is difficult, if not impossible, to secure the reversal of the screw at the particular turn or portion of a turn required, by either automatic or hand devices. The reverse of the positive feed is, in my invention, made to occur before the winding reaches the head of the spool. On account of the tension of the wire, and possibly the momentum of the swinging arm 29, the wire continues, notwithstanding the reverse of the screw, to be led toward the head of the spool where the reverse is required, the arm 29 swinging quite widely to one side for this purpose. As it continues to swing, its angular deviation from the perpendicular becomes greater so that the direction of the lead is slightly modified and tends to cause a reverse of the wind. When the head of the spool is

reached, this condition, taken together with the effect of the barrier or wall of the spool head, is sufficient to abruptly reverse the wire which thereupon proceeds to wind in the reverse direction of lead corresponding to the new movement of the lead screw. If the nature and requisites of the wire accord with the pitch of the lead screw, it is probable that the swinging arm will have but little further independent movement except to slightly return to its perpendicular position on account of the radial component of force upon the arm due to the tension of the wire. If, however, the resiliency and character of the wire requires momentarily a different feed from that of the positive lead screw, the swinging arm is always able to accommodate the particular need. When the lead approaches the other head of the spool, the operator, or the automatic devices, effect a reverse as in the previous instance, and the swinging arm continuing its movement applies or "whips" the wire toward the head of the spool and back again, making a smooth, precise and perfectly continuous winding, meeting all required practical conditions.

Adjustments.—I provide all necessary adjustments by which the machine is adapted to receive spools of different sizes and dimensions, to wind them with different sizes of wires, and to give the different turns varying feeds or pitch. I have referred to the adjustment of the head stock 4 and tail stock 5 by which they may receive different size spools. The gears 42, 43 and 45 are change gears, and may be varied to secure any desired speed or pitch. For this purpose the gear 43 is mounted in a slotted bearing in the usual manner of change gears. The vertical height of the wire carrying frame is adjustable by the nut 25 to suit different sizes of spools and different kinds of wire. It is evident that the separation of the guide wheel 32 from the spool would be greater in the case of large wires than small ones. If necessary the wire guiding frame may be made adjustable forwardly and back so as to adjust the inclination of the lead for different diameters of spools. It is evident that other adjustments may be provided, and I desire to include within my invention any ordinary adjustment of the various parts.

What I claim, is:—

1. A means for guiding wire in process of being wound upon a spool, comprising a wire guiding arm, a support for said arm movable in a rectilinear direction parallel to the spool, and means for reciprocally moving said support; said arm being freely movable with respect to the support in addition to the movement of said support, whereby said arm is constrained by the tension of the wire to guide the same with a

- regular feed or pitch during the major portion of the layers and to lead the reversal of the layers at the heads of the spools.
2. A means for winding wire upon a spool, comprising means for rotating a spool at a uniform rate of speed, an arm having a delivery device, a support for said arm to which the same is freely pivoted, and reversible mechanism independent of the arm and spool for moving said support with a predetermined pitch or feed along the spool, said arm having a further independent movement in the direction of feed after the said mechanism is reversed. 70
3. In a winding machine, means for holding a spool, means for continuously rotating the said holding means and spool, means for leading wire to the spool, said means being movable with a predetermined pitch or feed along the spool and having an independently movable guiding portion adapted to continue in motion after reversal of said means for subsequently leading the wire in the reverse direction at the heads of the spool, and means for reversing the direction of feed of said means. 75
4. In a winding machine, means for supporting a spool, means for continuously rotating the spool, means for leading wire to the spool, reversible mechanism for advancing said means with a predetermined pitch or feed reciprocally along the spool, and a guide independent of means for stopping and reversing said wire-supplying means, forming part of the said supplying means, movable independently thereof in the direction of feed after the feed has been stopped, whereby to lay the wire evenly and carry it to the heads of the spool. 80
5. In a winding machine, means for supporting a spool, means for continuously rotating the spool, a wire-carrying head mounted to travel parallel to the spool, positive means for driving said head with a predetermined pitch or feed in opposite directions, means for reversing said driving means, and a wire guide independent of said reversing means mounted on said head with provision for independent further motion in the direction of feed, whereby to lead the wire to, and reverse the same at, the heads of the spool. 85
6. In a winding machine, means for supporting a spool, means for continuously rotating the spool, means for leading wire to the spool, reversible mechanism for advancing said means with a predetermined pitch or feed reciprocally along the spool, a guide forming part of the said wire-leading means movable independently thereof in the direction of feed, whereby to lay the wire evenly and carry it to the heads of the spool, and devices independent of said means and guide for effecting reversal of said mechanism. 90
7. In a magnet winding machine, means for supporting a spool, means for continuously rotating the spool, a reciprocating wire-carrying head mounted to travel parallel to the spool with a predetermined feed, and an independently swinging arm, over which the wire is guided, pivoted to said head so as to swing in the directions of travel thereof, and caused by the wire to continue beyond the limits of reciprocation of the head to lay the wire evenly up to the ends of the spool and there reverse the windings. 95
8. A means for winding wire upon a spool comprising a support movable in a rectilinear direction parallel to the spool, an arm pivoted to said support and mounted to have a freely swinging movement through a wide arc on either side of its central position perpendicular to the spool, said arm having a delivery device, and means including driving devices and reversing means therefor, independent of said arm, for moving the support in its rectilinear path whereby the arm may be maintained substantially perpendicular to the spool during the progress of the layer. 100
9. A means for winding wire upon a spool comprising an arm mounted to have a freely swinging movement on either side of its central position perpendicular to the spool, said arm having a delivery device, a block to which said arm is freely pivoted, and means including a positive driving mechanism and reversing means therefor, for moving said block to and fro to accord with the progress of the layer upon the spool, said arm being independent of such reversing means. 105
10. In a magnet winding machine, means for supporting a spool, means for continuously rotating the spool, a threaded shaft parallel to the spool, means for rotating said shaft alternately in opposite directions, a wire carrying head guided by said threaded shaft, and a wire guiding arm swiveled upon said head and having an independent movement in addition to the movement of the head at the end of each reciprocation thereof beyond its central or normal position. 110
11. In a magnet winding machine, means for supporting a spool, means for continuously rotating the spool, a wire carrying frame guided to reciprocate parallel to the spool, power means for moving said frame back and forth at a rate corresponding to the rate of winding of the wire, a hand-operated reversing device whereby the direction of travel of said frame is governed, and a wire guiding arm swiveled to said frame, independent of said reversing device, having a frictionally-impeded swinging movement relatively to the frame. 115
12. In a magnet winding machine, means for supporting a spool, means for continu- 120

- ously rotating the spool, a wire carrying head guided to reciprocate parallel to the spool, a wire carrying frame supported by said head and vertically adjustable thereon, 5 means for maintaining the adjustment of said frame at one height, and an arm carried by said frame and swinging independently thereof.
13. In a magnet winding machine, means for supporting a spool, means for continuously rotating the spool, a lead screw connected to rotate therewith, a wire carrying head driven by said screw and having an independently swinging wire guiding arm mounted to swing to either side of its central or normal position, and means for reversing the direction of rotation of said lead screw to drive said head reversely. 10
14. In a magnet winding machine, means for supporting a spool, means for continuously rotating the spool, a lead screw connected to rotate therewith, a wire carrying head having an independent swinging wire guiding arm, friction means for impeding the movement of said arm relative to the head, and means for reversing the motion of said lead screw at any desired point of its movement. 15
15. In a magnet winding machine, means for supporting a spool, means for continuously rotating the spool, a threaded shaft connected to rotate therewith, a wire carrying head guided by said threaded shaft and having an independently swinging arm, friction means for impeding the swinging movement of said arm relative to said head, a clutch, and means independent of said arm for operating said clutch to reverse the direction of motion of said threaded shaft. 20
16. In a magnet winding machine, means for supporting a spool, means for continuously rotating the spool, a lead screw parallel thereto, a wire carrying head guided by said screw and having an independently swinging arm, said arm having a freely swinging movement to either side of its central or normal position for leading wire continuously in the previous direction after reversal of said head, gear connections between 25 said spool and lead screw, means for changing said gear connections, whereby a reversal of the lead screw is effected, and a hand device independent of said swinging arm for actuating said reverse. 30
17. In a magnet winding machine, means for supporting a spool, means for continuously rotating the spool, and wire-leading means guided to reciprocate parallel thereto, and including a relatively movable member governed by the wire for imparting an independent lateral movement to the wire, as it approaches the ends of the successive layers. 35
18. In a magnet winding machine, means for supporting a spool, means for continuously 40
- ously rotating the spool, wire-leading means guided to reciprocate parallel thereto, and means for driving and reversing said wire-leading means, said wire-leading means being composed in part of a member governed by the wire for imparting an independent lateral further movement to the wire, after reversal of the leading means as it approaches the end of each successive layer. 45
19. In a magnet winding machine, means for supporting a spool, means for continuously rotating the spool, a lead screw parallel to the spool, connections for rotating said lead screw synchronously with said spool, a wire carrying head engaged with said lead screw and fed thereby, a wire carrying frame adjustably attached to said head, and a wire guiding arm pivoted to said frame so as to swing independently thereof in the direction of feed. 50
20. In a magnet winding machine, means for supporting a spool, means for continuously rotating the spool, a lead screw parallel to the spool, connections for rotating said lead screw synchronously with said spool, a wire carrying head on said lead screw, a wire guiding arm swiveled upon said head, and guiding rollers upon said arm, said arm being caused to follow the motions of the head throughout the main portion of each layer, and arranged clear of the spool so that it is caused by the wire to make a slight independent movement at each end of the layer beyond the head toward the adjacent spool head. 55
21. In a magnet winding machine, means for supporting a spool, means for continuously rotating the spool, a wire-leading device guided to reciprocate parallel to the spool, with a predetermined pitch or feed, operator-controlled means for reversing the direction of feed of said device, and a member forming part of said device governed by the wire for effecting reversal of the windings thereof. 60
22. In a magnet winding machine, means for supporting a spool, means for continuously rotating the spool, a wire carrying frame, means for giving said frame a to-and-fro movement with a predetermined pitch or feed, hand-operated means for reversing the said frame, and means upon said frame for guiding the wire in the direction of said feed in addition to the movement given by said frame, whereby the latter is guided to reverse the layer at the heads of the spool. 65
23. In a winding machine of the character described, in combination with means for supporting a spool, means for continuously rotating the spool, and a wire-carrying head, mechanism for moving said head to and fro, including a clutch for reversing the movement of the head, a clutch shipper engaged with said clutch, and a lock constructed and 70

- arranged to engage said shipper positively and secure said shipper and clutch in either limit of their throw, arranged to prevent dislodgment thereof by any force applied 5 to the shipper or clutch in the direction of their movement, said lock being also the actuating means for throwing the shipper and clutch.
24. In a winding machine of the character 10 described, in combination with means for supporting a spool, means for continuously rotating the spool, and a wire-carrying head, mechanism for moving said head to and fro, a clutch for reversing the movement of the 15 head, and operating elements for shifting the clutch, said elements by their interengagement serving also to constitute positive abutments which retain the clutch in either extreme position and prevent dislodgment 20 by any other means.
25. In a magnet winding machine, means for supporting a spool, means for continuously rotating the spool, a wire carrying frame guided to move parallel to the spool, 25 a clutch for reversing the movement of said frame, and a shifting and locking block having cam surfaces for moving said clutch and locking it at each extreme position of its throw.
30. 26. In a magnet winding machine, means for supporting a spool, means for continuously rotating the spool, a wire carrying frame guided to move parallel to the spool, a clutch for reversing the movement of said 35 frame, a shifting and locking block con-
- nected to said clutch, a pair of reciprocating pins having shoulders contacting with said block, a transversely moving bar engaging said pins whereby the block and clutch are shifted to the extreme position of their throw and locked in such relation by the movements of said shifting bar.
27. In a winding machine, means for supporting, and means for rotating, the same, a wire-carrying head having independently 45 movable means thereon for leading the wire to the spool, gearing for effecting reverse movements of said wire-carrying head, a block having inclined cam surfaces for effecting said reversal, and pins bearing 50 against the inclined surfaces of said block for moving it to its extreme positions and locking it in such relation.
28. In a winding machine, a wire-carrying head having independently movable 55 means swinging freely to either side of its central or normal position thereon for leading the wire to the spool, a clutch, a transversely movable notched bar, and means cammed or wedged outward by the notches 60 of said bar for shifting said clutch to effect a reversal of movement of the wire-carrying head.

In witness whereof, I subscribe my signature, in the presence of two witnesses.

EUGENE R. PHILLIPS.
